UNITED STATES PATENT OFFICE.

FRANCIS BOYLE, OF NEW YORK, N. Y., ASSIGNOR TO UNITED STATES TIRE COMPANY,
A CORPORATION OF NEW YORK.

DESIGN FOR A CLOCK-CASING.

48,965.

Specification for Design.

Patented May 2, 1916.

Application filed February 18, 1915. Serial No. 9,187. Term of patent 3½ years.

To all whom it may concern:

Be it known that I, FRANCIS BOYLE, a citizen of the United States, residing in the city of New York, county and State of New York, have invented a new, original, and ornamental Design for Clock-Casings, of which the following is a specification, reference being had to the accompanying drawing, forming a part thereof.

The figure of the drawing is a front elevation of a clock casing embodying my new design.

Copies of this patent may be obtained for five cents each, by addressing the "Commissioner of Patents, Washington, D. C."

The design comprises a frame 10 of the shape of and fitting in the inclosure of a section of an elastic vehicle tire 11, or any simulation thereof, said frame surrounding the clock 12.

I claim:

The ornamental design for a clock casing, as shown.

FRANCIS BOYLE.
